LIQUID DELIVERY APPARATUS

George W. Stedwell, Brooklyn, N. Y., assignor to
 Keystone Controls, Inc., New York, N. Y., a
 corporation of New York

Original application September 17, 1930, Serial
 No. 482,410. Divided and this application May
 24, 1935, Serial No. 23,137

8 Claims. (Cl. 221—95)

The present invention is a division of my co-pending application Serial No. 482,410, filed September 17, 1930.

The present invention relates to the delivery of 5 gasoline and other liquids in metered quantities as covered in Hawkhurst Reissue Patent 17,558, wherein the return of the hose nozzle to its normal support effects an interlocking of parts automatically preventing delivery operation while the hose 10 remains in such supported relation.

Special objects of this invention are to improve on the structure and operation disclosed in the patent referred to and to provide simpler and more desirable apparatus.

15 Other purposes and advantages, as well as the novel features comprising the invention, will appear as the specification proceeds.

The drawing accompanying and forming part 20 of the specification illustrates several of the many possible embodiments of the invention, it being understood however that the structure may be further modified all within the broad spirit and scope of the invention.

Fig. 1 is a broken front elevation of a gasoline 25 dispensing stand having features of the invention incorporated therein; Fig. 2 is a fragmentary and part sectional illustration of a modification; Fig. 2a is a broken detail of the hook or nozzle support; Figs. 3 and 4 are fragmentary perspective and side views respectively of another form 30 of the invention.

In Fig. 1, the flow of liquid may be traced from the supply pipe 5 through pump 6 and delivery line 7 to the meter 8 and from this meter through 35 another section of the delivery line 9 into the delivery hose 10. This hose is shown equipped with means for effecting flow control in the form of a nozzle valve 11 actuated by a hand lever 12 protected by a handle guard 13. This guard is 40 shown as slotted at 14 back of the valve handle to fit over an upstanding supporting lug 15, which in the relation illustrated holds the valve handle so that it cannot be operated. In this supported relation, the tip of the nozzle passes up 45 through an opening in the side of the stand shown at 16 in Fig. 2, whereby the nozzle is firmly supported and operation of the valve handle is then prevented.

The pump is indicated as operated by an electric motor 17. This motor is controlled by a switch 18. The restoration of the nozzle to the supporting hook serves to automatically stop the operation of the pump, in the first form of the invention illustrated, by means of the nozzle guard 13 engaging and operating a push button

19 connected with the switch actuating lever 20.

For throwing the switch to start the motor, a push button 21 is provided, but actuation of this push button is prevented when the nozzle is on the hook by the connection of this lever through 5 a rocking lever 22 with the "off" button 19, the same constituting in effect a "walking beam" connection between the two push buttons 19 and 21.

To use the apparatus, the nozzle is lifted off the 10 hook. This frees the nozzle valve lever and leaves the switch free to be thrown to the "on" position, the latter operation being effected by pushing in on the button 21. With the closing of the switch, 15 the pump is started and liquid may then be delivered from the hose under control of the nozzle valve, the meter disclosing any amounts thus delivered. Delivery can be instantly terminated by releasing grip on the hand lever to close the 20 nozzle valve.

When a delivery is completed, the nozzle is restored to the hook and in so doing, the guard strikes the "off" button 19 of the hook forcing the same inward and causing the switch to stop 25 the pump. Thus by simply hanging up the hose in its supported relation, an interlocking of parts is effected, whereby unauthorized or accidental discharge of liquid is automatically prevented.

The structure shown in Figs. 2 and 2a is generally similar to that described, possibly, the 30 main distinction being that the tip of the nozzle instead of the nozzle guard is utilized to throw the switch to the "off" position upon the restoration of the nozzle to supported relation. Thus, in place of the upper or "off" push button, the 35 rocking lever 22 is provided with an extension 19a having a function equivalent to the push button 19 and extending across the nozzle opening 16 into the direct path of the nozzle, so as to be engaged and shifted by the latter as the nozzle 40 is placed on the hook. Also, the hook differs from that first disclosed in that instead of being a narrow upstanding lug as in the first instance, it is made heavier and provided with a recess 25 in one side to receive the lower portion of the 45 guard, this portion of the guard dropping into this recess behind a shoulder or stop 26, which prevents the guard from slipping sidewise out of the notch. The body of the supporting lug, which here is designated 15a serves to interlock 50 with and prevent operation of the hand lever in the same manner as in Fig. 1 and except for the fact that the guard is entered sidewise on the hook and the end of the nozzle instead of the guard 55 effects the "off" movement of the switch, the op-

eration may be considered the same as in the first illustration.

- 5 In the form of the invention shown in Figs. 3 and 4, the switch is directly operated by hand instead of through the medium of the hose nozzle, by means of a rock shaft 27 carrying a lever 28 engaged with a switch lever and provided outside the case with a hand lever 29, which under operating conditions of the pump stands in the way 10 of the nozzle restoration and is in turn held against operation when the nozzle is on the hook. The hook here designated 30 is shown as having an upstanding lug 15b received in a recess 31 in the side of the guard and adapted to stand back 15 of the nozzle valve lever 12, Fig. 4. In this supported position, the switch lever 29 in its upper, "off" position is in line with and held against operation by the hand lever 12. Consequently, the nozzle valve can not be opened and the pump 20 cannot be started when the nozzle is supported on the hook. The removal of the nozzle from the hook however, leaves the nozzle valve free for operation and uncovers the switch lever 29, so that it may be turned down to the "on" position 25 of the pump illustrated in full lines in Fig. 3. In this condition it stands in the way of the nozzle guard, thereby effectively preventing the nozzle from being restored to the hook until the switch has first been thrown to stop the pump motor.
- 30 The structure in all forms of the invention is simple and positive and automatically prevents improper operation of the apparatus. When the nozzle is placed on the hook, the parts interlock in a way to automatically prevent delivery operations 35 and the pump cannot be started until the hose has been taken off the hook. Further, a positive act on the part of the attendant is necessary even after the hose has been removed from the hook. In Figs. 1 and 2, the push button 21 40 must be actuated and in Figs. 3, 4, the hand lever 29 must be turned down to the motor starting position. In Figs. 1 and 2, the act of placing the nozzle on the hook shuts off the pump motor. Substantially the same result is accomplished in 45 Figs. 3 and 4 in that the nozzle can not be placed on the hook until the lever 29 is turned to throw the switch. When the hose is off the support, the actuating means for the controller is freely operable at all times to stop the pump, so that 50 with the hose off the hook, the pump may be started and stopped at will. Thus with the hose off the hook, the pump may be stopped and the nozzle valve be opened to completely drain the 55 hose. On the other hand, if the hose is restored to the hook full of liquid under pressure, the nozzle handle becomes locked, so that it may not be operated accidentally or otherwise to discharge any of the liquid under pressure held in the delivery line and hose.
- 60 What is claimed is:
1. In liquid flow apparatus, a hose having a nozzle, a support for the nozzle structure, liquid flow governing means for the hose, a controller for said liquid flow governing means and push button actuating mechanism for said controller and including inter-connected parts, one positioned to be shifted and held by the nozzle structure upon the placement of the latter on the support and adapted by its interconnection with the other to thereupon secure said other part against operation while the nozzle is on the support and said other part being freed for operating the controller when the nozzle structure is removed from the support.
  2. In liquid flow apparatus, the combination of

5 a hose provided with a nozzle valve, a handle for actuating said nozzle valve, a guard extending about said nozzle valve handle and a support for said nozzle valve, said support being recessed to receive a portion of said guard and laterally extended to permit a lateral shifting movement of the guard in said support and said support having a body portion positioned to enter laterally between the nozzle valve and said handle to prevent operation of the latter when the nozzle guard 10 is shifted laterally as described.

3. In liquid flow apparatus, the combination of a hose provided with a nozzle valve, a handle for actuating said nozzle valve, a guard extending about said nozzle valve handle and a support for 15 said nozzle valve, said support being recessed to receive a portion of said guard and laterally extended to permit a lateral shifting movement of the guard in said support, said support having a body portion positioned to enter laterally between 20 the nozzle valve and said handle to prevent operation of the latter when the nozzle guard is shifted laterally as described and a shoulder positioned to hold the nozzle guard in said laterally shifted position with the nozzle valve handle held by the 25 body portion aforesaid.

4. In liquid flow apparatus, the combination of a hose provided with a nozzle valve, a handle for actuating said nozzle valve, a guard extending about said nozzle valve handle and a support for 30 said nozzle valve, said support being recessed to receive a portion of said guard and laterally extended to permit a lateral shifting movement of the guard in said support and said support having a body portion positioned to interlock with 35 the nozzle valve handle to prevent operation of the latter when the nozzle guard is shifted laterally as described, said nozzle support comprising a lug and the recess described being extended laterally inwardly from one side of said lug and 40 a shoulder being provided on said lug at the entrance to said recess to hold the inserted guard portion in the laterally shifted relation with the body portion of the lug interlocked with the 45 nozzle valve handle.

5. In an apparatus of the character described, a delivery line terminating in a hose, a nozzle at the free end of the hose, a support for the nozzle when not in use, a motor driven pump arranged to supply the delivery line and hose with 50 liquid under pressure, and means for starting and stopping the pump, said means including a controller having two parts interconnected for movement in mutually opposite directions, one of the parts being so related to the support as to 55 be moved by the nozzle to stop the pump when the nozzle is placed on the support and the other part being movable manually when the nozzle is off the support to start the pump.

6. An apparatus of the character described, 60 comprising a housing structure, a liquid delivery line passing through the housing and terminating in a flexible hose outside of the housing, a nozzle at the free end of the hose, said nozzle comprising a body portion and a spout portion, 65 the housing being provided with an opening to receive the spout portion and a support to receive the body portion when the nozzle is not in use, a liquid flow governing means for the delivery line and hose, a controller for said means having 70 two shiftable parts interconnected for movement in mutually opposite directions, one of the parts being shiftable manually to start the flow when the nozzle is off the support and the other part being disposed in such position with respect to 75

said opening as to be shifted by the spout to stop the flow when the nozzle is returned to the support.

5. An apparatus of the character described, comprising a housing structure, a liquid delivery line passing through the housing and terminating in a flexible hose outside the housing, a nozzle at the free end of the hose, said nozzle comprising a body portion and a spout portion, the housing being provided with an opening to receive the spout portion and a support to receive the body portion when the nozzle is not in use, a motor driven pump adapted to supply the delivery line and hose with liquid under pressure, and means for starting and stopping the pump, said means comprising a controller having two shiftable parts interconnected for movement in mutually opposite directions, one of the parts being shiftable manually to start the pump when the nozzle is off the support and the other part

being disposed in such position with respect to said opening as to be shifted by the spout to stop the pump when the nozzle is returned to the support.

8. Dispensing apparatus including a delivery hose having a nozzle provided with a control valve, means carried by the nozzle for actuating the control valve, said nozzle having a guard comprising a loop encircling said actuating means, a support for the nozzle, when idle, having locking means adapted to extend transversely into the loop and between the valve-actuating means and the body of the nozzle in order to prevent operation of the actuating means when the nozzle is on the support, said support being 10 formed with a portion adapted to encircle at least 15 a portion of the guard whereby to provide a recess for receiving the encircled portion.

GEORGE W. STEDWELL.
